UNITED STATES PATENT OFFICE.

EDWARD S. SMITHSON, OF MONMOUTH, ILLINOIS.

DESIGN FOR A POTTERY-JAR.

No. 38,859.

Specification for Design.

Patented Oct. 15, 1907.

Application filed August 23, 1907. Serial No. 389,916. Term of patent 3½ years.

To all whom it may concern:

Be it known that I, EDWARD SYLVESTER SMITHSON, a citizen of the United States, residing at Monmouth, in the county of Warren and State of Illinois, have invented a new, original, and ornamental Design for Pottery-Jars, of which the following is a specification, reference being had to the accompanying drawing, which is hereunto annexed and is a part thereof.

The figure is a side elevation of a pottery jar showing my new design.

I claim:

The ornamental design for a pottery jar, as shown.

E. S. SMITHSON.
